UNITED STATES PATENT OFFICE

JOHN POMEROY GATY, OF MADISON, NEW JERSEY

SOUND-PROPAGATING DIAPHRAGM

Application filed May 2, 1928. Serial No. 274,598.

The invention relates to means for actuating sound propagating diaphragms.

One object of the invention is to provide improved means for attaching an actuating arm to a sound propagating diaphragm of a laminated or composite type.

Further objects of the invention are to provide means for the attachment of an actuating arm to a composite sound propagating diaphragm whereby the energy for vibrating the diaphragm will be applied internally of the diaphragm.

A still further object of the invention is to provide means within a sound propagating diaphragm for cooperation with an actuating arm to retard the movement of the faces of the diaphragm with respect to the actuating arm.

One feature of the invention relates to the securing of an actuating arm to an attaching plate positioned internally of a composite sound propagating diaphragm.

Another feature of the invention relates to the provision of air cells between point of attachment of an actuating arm and the surfaces of a sound propagating diaphragm whereby a dampening of the vibration is effected.

Other objects and features will appear from the following description in connection with the accompanying drawings in which—

Figure 1 of the drawings is a sectional view of a sound propagating apparatus embodying the present invention.

Figure 2 is a detail view of the present invention shown in section.

Like reference characters denote like parts in the several figures of the drawing.

In the following description and claims, parts, characteristic features and functions will be identified by specific means for convenience of expression, but they are intended to be as generic in their application to similar parts or equivalent construction as the art will permit.

Referring to the drawings, for supporting a sound propagating diaphragm a base 10 is provided carrying a supporting rim 11 to which the diaphragm is secured by a retaining rim 12. A supporting arm 13 is also

provided secured to the rim 11 for supporting electromagnetic unit 14 to which is secured an actuating arm 15 for imparting vibration to the sound propagating diaphragm.

For controlling the electromagnetic unit 14 in accordance with a signal wave, there is provided an energy responsive device 20, shown in the form of an antenna positioned to intercept radiant energy or so-called Hertzian waves. It is understood that such waves may be emitted from a radio broadcast station of a conventional type, but as the emission of such energy forms no part of the present invention, it is thought that a detailed description thereof may be omitted herein. The emitted energy preferably takes the form of a carrier wave of high frequency modulated in accordance with a signal current, the signal current corresponding in wave form to sound waves. The antenna 20 at the receiving station is operatively connected to a tuner 21, a ground or counterpoise 22 being provided therefor. The tuner 21 may be variably adjusted so as to tune the circuits 20, 22 to the frequency of the carrier wave which it is desired to receive and a connection comprising a pair of wires 23—23 extends from the tuner 21 to a detector 24 for impressing thereon electrical waves of this predetermined frequency. The detector 24 may be of any usual form for detecting high frequency energy and producing therefrom rectified or detected waves of signal frequency. These signal waves are transmitted over a pair of conductors 25 extending to the input of an amplifier 26 whereby the signal energy is amplified to a desired degree. A pair of conductors 27 forms an operative connection from the output of the amplifier 26 to the electromagnetic unit 14. Thus undulatory current of signal frequency is impressed upon the electromagnetic unit 14 under control of received radiant energy.

For propagating sound waves a composite diaphragm 30 is provided preferably formed of a plurality of sheets of fibrous material such as paper or the like including a central sheet 31 and a pair of external facing sheets 32 and 33 respectively, spaced from

said central sheet by a pair of deformed or corrugated fibrous sheets 34 and 35. In some instances it may be desirable to provide a sizing such as aeroplane dope on one face of the diaphragm as at 36. Diaphragms of this character are especially adapted for the propagation of sound waves of the lower portion of the musical register due to the damping effect of the air cells 28 formed by the deformed sheets 34 and 35. 10 By altering the weight and texture of the opposite sides of the diaphragm by sizing, sound waves of different characteristics may be propagated from the opposite faces of the diaphragm. 15 For imparting vibration to the sound propagating diaphragm 30 an attachment plate 40 is provided secured to one face of the central sheet 31 as by gluing or the like. Rigidly secured to the plate 40 is an actuating arm 41 through which impulses from the electromagnetic unit 14 are imparted to the attachment plate 40 which in turn imparts similar vibrations to the facing sheets 20 32 and 33. Movements of the facing sheets 32 and 33 are damped by the passage of the actuating movement through the deformed sheets 34 and 35 and air cells 28 formed between the central sheet 31, the facing sheets 32 and 33 and the deformed sheets 34 and 35.

For operatively connecting the actuating arm 15 to the actuating arm 41 a clutch mechanism 50 is provided comprising an externally threaded split cup shaped member 51 surrounded by conical internally threaded member 52 coacting with the external thread of the member 51, whereby when the actuating arm is positioned within the member 51 adjustment of the internally threaded member 52 will cause the side faces of the member 51 to securely engage the actuating arm 15.

Thus it may be seen that the invention 45 provides a novel means of actuating a sound propagating diaphragm of the composite type whereby the vibrations imparted by an actuating unit will be damped before causing vibrations of the surfaces of the dia- 50 phragm.

The invention upon which this application is based is broader than the specific embodiments shown and described for the purpose of illustrating at least some of the 55 ways in which it may be employed. The scope of the invention is therefore to be understood as not being limited by the present specific description. I intend no limitations other than those imposed by the claims.

60 What is claimed is:

1. A sound propagating apparatus comprising in combination a diaphragm, having spaced outer faces, an actuating unit, and 65 means for imparting motion from said actu-

ating unit to a point between the faces of said diaphragm.

2. Means for propagating sound waves from a sound propagating diaphragm having substantial thickness comprising an attaching plate positioned within said diaphragm and an actuating arm secured to 70 said attaching plate and means for connecting said actuating arm to an actuating unit.

3. In combination with the sound propagating diaphragm having substantial thickness an attaching plate positioned internally of said diaphragm, an actuating arm attached to said attaching plate and means 75 for imparting vibration to said actuating arm.

4. Means for propagating sound waves from a composite sound propagating diaphragm formed of a plurality of sheets comprising an attaching plate secured between the sheets of said diaphragm and an actuating arm connected to said attaching plate. 85

5. A sound propagating diaphragm comprising a central sheet, deformed spacing members positioned on either side of said sheet, and facing sheets forming the outer surface of said diaphragm attached to said deformed sheets and means for attaching an actuating arm to said central sheet. 90

6. Means for dampening the vibrations of a sound propagating diaphragm with respect to the vibrations of an actuating means comprising a plurality of air cushioning means between the faces of said diaphragm and an attaching plate positioned between said air cushioning means. 100

Signed at New York, in the county of New York and State of New York, this 17th day of January, A. D. 1928.
